UNITED STATES PATENT OFFICE.

JOHN L. HALL, OF SCHENECTADY, NEW YORK, ASSIGNOR TO GENERAL ELECTRIC COMPANY, A CORPORATION OF NEW YORK.

ARC-CONTROL MECHANISM FOR PROJECTORS.

1,101,629.

Specification of Letters Patent. Patented June 30, 1914.

Application filed March 28, 1908. Serial No. 422,253.

To all whom it may concern:

Be it known that I, JOHN L. HALL, a citizen of the United States, residing at Schenectady, in the county of Schenectady, State 5 of New York, have invented certain new and useful Improvements in Arc-Control Mechanism for Projectors, of which the following is a specification.

My invention relates to arc controlling mechanism, and more particularly to the mechanism by which the length and position of the arc is controlled in searchlights, projectors and similar devices in which an arc is used as a source of light.

15 The arc control mechanism for projectors heretofore used has usually been provided with an automatic feeding device which can advance the electrodes toward each other after the arc is established or struck by 20 means of a series magnet, and thereby diminish the gap between them to compensate for the consumption of the carbons while burning, but which is unable to feed the electrodes through varying small 25 amounts and thereby increase the gap between them to compensate for arc changes. In large projectors and similar devices, especially where large carbon electrodes are used the arc current and volts vary depending 30 on the crater formation and carbon texture and cause a sudden decrease as well as increase of the arc drop, making it desirable to automatically increase as well as decrease the arc length to maintain constant 35 condition and even illumination.

The object of my invention is to provide a control mechanism for the arc which will automatically, accurately and rapidly either increase or diminish the gap between the 40 electrodes and thereby maintain a constant arc condition; which in searchlights will, by feeding both carbons or electrodes, maintain the arc in approximately the same position during their consumption, and which 45 is in general an improvement in the construction and operation of arc control mechanism, particularly for searchlights and projectors.

In carrying out my invention I provide 50 means for automatically increasing as well as diminishing the gap between the electrodes so that the arc is always of constant length. In the preferred arrangement for a projector both electrodes move and the adjustment of arc length is therefore very

rapid and exact, and by properly proportioning the feed of the two carbons to correspond to the relative sizes of the two carbons the arc will be maintained in approximately the focus of the lens or mirror. The 60 adjustment of the gap between the electrodes to maintain the arc length constant is preferably controlled by some automatic regulating device which responds to variations in potential between the electrodes. 65 Such a regulating device may assume many different forms, but in the preferred arrangement some suitable motor or driving mechanism is arranged to move one or both electrodes either to increase or diminish the gap 70 between the electrodes, and is controlled by a relay or pilot device which determines both the direction and extent of movement required to keep the arc length constant. The relay is made very sensitive and is connected so that in one position it causes the 75 driving mechanism to increase the gap between the electrodes until normal arc length is secured, while in another position it causes the driving mechanism to diminish the gap 80 between the electrodes until the arc length becomes normal. The relay, which may be in the form of an electromagnet, is made responsive to potential between the electrodes by being connected in parallel with 85 them, and controls the driving mechanism in any suitable way, preferably by means of a locking mechanism which instantly and positively stops and holds the driving mechanism and instantly releases it so that the 90 driving mechanism starts without delay and is instantly stopped without overrunning. The relay is preferably, though not necessarily, provided with a series coil connected in series with the arc and wound to oppose 95 the shunt coil, which is connected in parallel with the arc. By using a sensitive relay to control a powerful motor or driving mechanism directly connected across the line a very quick, powerful and accurate adjustment of the length of the gap between the 100 electrodes is secured, even though the adjustment requires a large and heavy electrode to be quickly moved in either direction.

My invention will best be understood in connection with the accompanying drawings, which show one of the many forms in which it may be embodied and in which—

Figure 1 is a diagrammatic view show- 110

ing the relation of the regulating and feeding mechanisms to the electrodes; Fig. 2 is a side view of a projector embodying my invention with the electrode supports shown in dotted lines; Fig. 3 is a plan view of the framework for guiding the electrode supports, said framework containing electrode-actuating mechanism of a form built and in use; Fig. 4 is a vertical longitudinal section of the construction shown in Fig. 3, with the actuating mechanism shown in elevation; and Fig. 5 is an end view of the construction shown in Fig. 3, with the ratchets and pawls for actuating the feed screws shown in elevation.

In the specific form shown in the drawings for purposes of illustration, the arc is drawn between electrodes 1 and 2, mounted on and carried by suitable supports or holders 3 and 4, which are both moved by any suitable actuating mechanism responsive to voltage across the arc to increase or diminish the gap between the electrodes and thereby maintain the arc length constant. The supports or holders may be made movable in any desired manner, preferably by mounting them on carriages 5 and 6, which slide on guides in a framework and are moved toward and away from each other by any suitable feeding mechanism which forms part of the actuating mechanism for the electrodes. In the particular construction shown in the drawing, the carriage 5 is provided at each end with grooved wheels 5^a which run upon guide rails 5^b. The electrode support 3 is rigidly secured to the carriage 5, but is insulated from it by insulation 5^c, while current is delivered to the electrode support 3 and the electrode 1 through a flexible U-shaped connection 3^a, formed of a plurality of thin strips of copper each with one end secured to the support 3, while the other end is secured to a flat bar 3^b connected to one lead of the circuit which supplies current to the projector. The other carriage 6 is provided with grooved wheels 6^a which run upon suitably shaped guide rails 6^b and the electrode support 4 is mechanically secured to the carriage but insulated from it by means of insulation 6^c. Current is supplied to the electrode support 4 through a flexible connection 4^a made of flexible strips of copper each connected at one end to the electrode support 4 and at the other end to the bar 4^b, which in turn is connected to the vertical bar 4^c to which current is supplied from the other lead of the supply circuit through connections hereinafter described. The form of feeding mechanism shown in the drawings consists of a feed screw 7 engaging a nut 5^d on the carriage 5 and a feed screw 8 engaging a nut 6^d on the carriage 6, the two feed screws being geared together through gearing 9 and 10 so proportioned that the electrodes are fed toward each other at such

a rate that the arc remains in practically the same position, notwithstanding the fact that one electrode is consumed more rapidly and is considerably larger than the other.

The actuating mechanism for increasing and diminishing the gap between the electrodes also comprises in addition to the carriages and feed screws above described some kind of a motor or actuating device for rotating the feed screws in one direction or the other to cause the two electrodes to approach or to recede from each other. Any motor or driving mechanism by means of which the feed screws may be rotated in either direction is suitable for this purpose, but the preferred form of actuating mechanism or motor is that shown in the drawings, in which a ratchet wheel 11 mounted on the feed screw 8 is engaged by a pawl 12 and is rotated in one direction when the pawl is actuated, and is also engaged by another pawl 13 by which it may be rotated in the other direction. The pawls 12 and 13 are actuated by suitable connections 14 and 15, shown diagrammatically in Fig. 1 as bell crank levers, and which in the specific form shown in the other figures are projections or lugs on pivoted armatures 16 and 17 moved by means of an actuating magnet 18 connected directly across the supply circuit and thereby subjected to the full difference of potential on the supply circuit. The circuit of the magnet 18 is broken at two gaps comprising rigid contacts 19 and 20 arranged, as shown in Fig. 1, so that the closure of either gap completes the circuit through the electromagnet, while the armatures 16 and 17 extend beyond their pivots and carry yielding contacts 21 and 22, which engage the contacts 19 and 20 when the armatures are drawn away from the magnet by a spring 23, and thereby complete the circuit and energize the magnet 18. The contacts for controlling the circuit of the electromagnet 18 may be made in various ways but are preferably constructed as shown in the drawing, in which the yielding contacts 21 and 22 are in the form of U-shaped spring blades secured to the armatures in a position to engage the rigid contacts 19 and 20. As best shown in Figs. 3 and 5, the extent to which the yielding contact can move toward the fixed contact is determined by control studs 21^a and 22^a which are mounted on the armatures and are provided with heads extending through slots in the yielding contacts. This construction permits the yielding contact to move toward the armature as far as may be necessary, but insures that the yielding contact will be drawn away from the stationary contact as the armature is attracted into engagement with the electromagnet 18. As shown in Fig. 1, each armature completes the circuit of the electromagnet and energizes it when the armature is drawn away from the magnet by the spring,

while the movement of the armature into engagement with the magnet causes the yielding contact on the armature to open the gap in the circuit of the magnet, whereupon the armature drops back to its original position. Either of the armatures 16 or 17 will, if unrestrained, vibrate rapidly and strongly as long as the electromagnet 18 is connected to the circuit.

10 The mechanism above described constitutes the motor part of an actuating mechanism for the electrodes, in which the vibration of the armature 16 will actuate the ratchet wheel 11 and the feed screws 7 and 8 and cause the electrodes 1 and 2 to approach each other and diminish the gap between them, while the vibration of the other armature will drive the ratchet wheel 11 in the reverse direction and cause the electrodes to move apart and increase the gap between them. Since both electrodes are movable and the armatures 16 and 17 vibrate with strong impulses and at high speed when they are unrestrained, the adjustment of the electrodes with relation to each other is accomplished very quickly and the length of the arc remains substantially constant.

In order to secure the best results the actuating mechanism for controlling the gap between the electrodes should automatically respond to variations in the potential between the electrodes to maintain the length of the arc and the difference of potential between the electrodes constant. In the projectors heretofore used a shunt coil, connected in parallel with the arc was arranged to feed the electrodes toward each other as the gap between the electrodes became too great, but had the disadvantage of not providing any means for increasing the gap between the electrodes in case the arc became too short, and also the disadvantage that a very sensitive coil did not have sufficient power to operate the electrodes satisfactorily; while a coil powerful enough to move the electrodes quickly was not sufficiently sensitive to variations in voltage. Where large electrodes are used the variation in the arc characteristics may make a very considerable difference in the difference of potential between the electrodes, and if the arc is to be maintained at constant length, the gap between the electrodes must be either increased or decreased very quickly by some comparatively powerful actuating mechanism, which moves one or both of the electrodes. In my invention this result is attained by making the motor or driving mechanism for moving one or both of the electrodes as powerful as may be necessary, and the entire actuating mechanism for controlling the gap between the electrodes is made responsive to variations of the potential between the electrodes by the use of a relay, or similar selective device, which is

responsive to said variations and controls the motor or driving mechanism in any suitable manner, preferably mechanically through some locking device or mechanism which will instantly release the driving mechanism and permit it to run and will instantly and positively stop and hold it in any desired position, thereby avoiding the use of electrical contacts which may become oxidized. Since the work the relay is called upon to do is very light it may be made as sensitive as desired and may be made in many different forms and connected in various ways so long as it is responsive to the variations in arc length. The preferred arrangement, as shown in the drawings, is one in which, between the regulating resistance 24 and the electrode 1, a relay magnet comprising a shunt coil 25 is connected across the circuit in parallel with the electrodes 1 and 2. It is preferable but not necessary to connect in series with the arc, a series coil 26 differentially wound as regards the shunt coil 25, and mounted upon a core 27 common to both coils so that the magnetization of the core 27 of the relay or pilot magnet depends on both the shunt current due to the difference of potential between the electrodes 1 and 2, and also with the current flowing between the electrodes and depends on the algebraic sum of the two excitations caused by said currents. In the specific arrangement shown in the drawings, the series coil 26 is connected in series with the electrode support 4 by means of connection bar 26^a, which joins one end of the series coil to the bar 4^c and by means of a curved connection bar 26^b, which joins the other end of the series coil to a flat bar or lead 26^c, which in turn is connected to a binding post by means of which one of the leads of the supply circuit may be secured to the projector. In the operation of the device the current flows from one lead of the supply circuit to the flat bar 3^b, thence through the flexible U-shaped connector 3^a to the electrode support 3 and electrode 1, thence through the arc to the electrode 2, through the electrode support 4 and the flexible connector 4^a to connector bars 4^b and 4^c, thence through the conductor 26^a, series coil 26, U-shaped connection 26^b, and the connecting bar 26^c to the other lead of the supply circuit.

The relay or pilot magnet may control the motor or driving mechanism for one or both electrodes by means of any suitable locking or controlling mechanism; but a form of control particularly adapted to the control of the driving mechanism illustrated in the drawings comprises an armature 28 responsive to the relay or pilot magnet, and connected to a pivoted latch or detent 29, which normally, under the influence of gravity, or of a spring, tends to engage the armature 16

and hold it against the magnet 18 in the inoperative position shown in Fig. 1. At the other end of the relay magnet a corresponding armature 30 is connected to a pivoted latch 31, controlled by a spring 32 normally tending to move the armature 30 away from the relay magnet and to move the latch 31 into the position shown in Fig. 1, where the armature 17 is free to vibrate under the influence of the spring 23 and of the magnet 18.

The various parts are so proportioned that when the current through the relay magnet is normal, both detents 29 and 31 restrain the two armatures 16 and 17 against movement; but if the potential between the electrodes varies and consequently the current increases above, or decreases below its normal value, the relay and its armatures respond to the variations of potential, and one or the other of the detents is moved and releases its armature, which thereupon begins to vibrate and the necessary adjustment in the gap between the electrodes 1 and 2 is made very quickly and accurately. The driving mechanism always tends or is biased to operate the adjusting mechanism as long as there is a difference of potential on the supply leads of the projector and consequently the driving mechanism begins to act the instant the detent is lifted and the mechanism is free. Owing to the comparatively light weight of the moving parts as compared with the force exerted by the electromagnet 18 there is practically no inertia or time lag in starting the mechanism and on the other hand it is stopped instantly and in the exact position desired when one or the other of the detents 29 or 31 drops into locking position and holds the corresponding armature immovable. As a result of this construction, the tendency of the driving mechanism to overrun and move the electrode support beyond the desired position is overcome and the adjustment of the electrodes is made much more accurately and quickly than where a motor or similar device having considerable inertia is used as the driving mechanism.

The operation of the device is as follows: If it be assumed that with the parts in the position shown in Fig. 1 the electrodes 1 and 2 are too close together, then the resistance between them is below the normal, and as a result the amount of current flowing through the shunt coil 25 is considerably below the normal. The slight increase in the amount of current flowing through the series coils is unable to counteract the effect of the shunt coil; and the spring 32 pulls the detent 31 into the position shown in Fig. 1, moving the armature 30 away from the core 27, and leaving armature 17 of the driving mechanism free to vibrate. The spring 23 immediately pulls the armature

17 into the position shown in Fig. 1, thereby causing the bridging contact 22 to close the circuit of the magnet 18 through the gap formed between two stationary contacts 20. As soon as this occurs the magnet 18 is subjected to the full potential of the supply circuit across the line, and the armature 17 begins to vibrate rapidly, making and breaking the circuit of the magnet 18, and at the same time vibrating the bell-crank lever 15 and the pawl 13, and causing a rotation in one direction of the feed screws 8 and 7. The rotation of the feed screws moves the electrode holders 3 and 4 and causes a separation of the electrodes and a corresponding increase in the gap between them. As a result of the increase in the gap the resistance of the arc and the difference of potential between the electrodes increase, causing more and more current to flow through the shunt coil 25. The mechanism continues to operate and to increase the gap between the electrodes until the current through the shunt coil 25 reaches such a value that the relay magnet is enabled to draw the armature 30 down against the spring 32, and thereby bring the detent 31 into the position to engage and hold the armature 17 against the magnet 18 and restrain it from further movement. As the arc continues to burn the carbons waste away, and eventually the length of the arc and the difference of potential between the electrodes become greater than normal. When this occurs a current greater than normal is flowing through the shunt coil 25, energizing the relay magnet to a point where it is enabled to pick up the armature 28 and thereby lift the detent 29 out of engagement with the armature 16. When this occurs the spring 23 draws the armature 16 away from the magnet 18, and simultaneously closes the circuit of the magnet through the gap formed between stationary contacts 19, whereupon the armature 16 begins to vibrate and moves and actuates through the bell crank 14 and pawl 12, and thereby drives the feed screw 8 and the feed screw 7 in the reverse direction. The movement of the feed screws in the reverse direction shifts the supports 3 and 4, and causes the electrodes 1 and 2 to approach each other and correspondingly diminish the gap between them. The vibration of the armature 16 continues until the arc length and the difference of potential between the electrodes 1 and 2 becomes normal, whereupon the current through the shunt coil 25 diminishes to such a point that the relay magnet is unable to hold the armature 28 and the detent 29 out of the locking position, so that the armature and detent drop and lock the armature 16 in the inoperative position shown in Fig. 1. These operations are repeated as the length of the

arc fluctuates on each side of the normal, and since the relay or pilot magnet is sensitive, and the motor or driving mechanism is powerful, the required adjustment of the gap between the electrodes is made very quickly, and the length of the arc remains substantially constant during the operation of the device.

My invention may be embodied in many other forms than that shown and described, and I, therefore, do not wish to be restricted to the precise form disclosed, but intend to cover by the appended claims all changes and modifications within the spirit or scope of my invention.

What I claim as new and desire to secure by Letters Patent of the United States, is,—

1. In an arc control mechanism, the combination with electrodes movable in two directions to vary the arc between them, of electrically controlled step-by-step mechanisms comprising two pawls and a common ratchet for moving said electrodes one pawl for moving them in one direction and the other for moving them in the other direction, and electrically controlled means for locking said mechanisms against movement in either or both directions.

2. In an arc control mechanism, the combination with a movable support for an electrode, of an actuating electromagnet having two pivoted armatures, each arranged to make and break the circuit of said electromagnet, feed mechanism for said support actuated by one armature to increase and by the other armature to decrease the gap between the electrodes, and means responsive to variations of potential between the electrodes for locking either or both of said armatures against movement.

3. In an arc control mechanism, the combination with a movable support for an elec-

trode, of electroresponsive actuating mechanism permanently connected to the supply leads and comprising a movable member biased to close the circuit of said mechanism and arranged to periodically open said circuit when in operation, a locking device for positively holding said member stationary in circuit opening position and electroresponsive means connected to said locking device to control said movable member.

4. In an arc control mechanism, the combination with movable supports for a pair of electrodes, of electro-responsive actuating mechanism permanently connected to the supply leads and comprising a pair of movable members either of which is adapted to close the circuit of said mechanism and to periodically open the same when in operation, locking devices coöoperating with said members to positively hold the same stationary in circuit-opening position, and electroresponsive means for selectively releasing said locking devices.

5. In an arc control mechanism, the combination with movable supports for a pair of electrodes, of electro-responsive actuating mechanism permanently connected to the supply leads and comprising a pair of movable members either of which is adapted to close the circuit of said mechanism and to periodically open the same when in operation, and means for locking said movable members and for selectively releasing the same comprising an electro-magnet and two coöoperating armatures for operating the respective locks.

In witness whereof, I have hereunto set my hand this 19th day of March, 1908.

JOHN L. HALL.
